US00D632484S

(12) **United States Design Patent**
Jimenez et al.

(10) **Patent No.:** US D632,484 S
(45) **Date of Patent:** ** Feb. 15, 2011

(54) **TOOTHBRUSH HANDLE WITH TISSUE CLEANER**

(76) Inventors: **Eduardo Jimenez**, 21 Manor Dr., Manalapan, NJ (US) 07752; **Michael Rooney**, 63 Locust Ave., Millburn, NJ (US) 07040; **Robert Moskovich**, 20 Jensen St., East Brunswick, NJ (US) 08816; **Andreas Wechsler**, Alfred-Kubin-Str.11, 5700 Zell am See (AT); **Joachim Storz**, Von Götz Weg 15-16, 5700 Zell am See (AT); **Raimund Klausegger**, Museumsplatz 1/5/8, 1070 Vienna (AT)

(**) Term: **14 Years**

(21) Appl. No.: **29/352,270**

(22) Filed: **Dec. 18, 2009**

(51) LOC (9) Cl. **04-02**

(52) U.S. Cl. **D4/108**

(58) **Field of Classification Search** D4/104-112, D4/134, 138; 15/110, 143.1, 167.1, 167.2; 132/308-311; 601/139, 141; D24/146, 152; 606/161

See application file for complete search history.

(57) **CLAIM**

The ornamental design for a toothbrush handle with tissue cleaner, as shown and described.

DESCRIPTION

FIG. 1 is a right front perspective view of a toothbrush handle with tissue cleaner according to the new design;

FIG. 2 is a left front perspective view thereof;

FIG. 3 is a right rear perspective view thereof;

FIG. 4 is a left rear perspective view thereof;

FIG. 5 is a front view thereof;

FIG. 6 is a rear view thereof;

FIG. 7 is a right side view thereof;

FIG. 8 is a left side view thereof;

FIG. 9 is top view thereof; and,

FIG. 10 is a bottom view thereof.

All broken lines shown in the drawings are for environmental purposes only and form no part of the claimed design.

1 Claim, 5 Drawing Sheets
